(57) **CLAIM**

The ornamental design for a pickleball paddle as shown and described.

DESCRIPTION

FIG. 1 illustrates a left frontal perspective view of a pickleball paddle showing our new design.

FIG. 2 illustrates a front view thereof.

FIG. 3 illustrates a rear view thereof.

FIG. 4 illustrates a right side view thereof.

FIG. 5 illustrates a left side view thereof.

FIG. 6 illustrates top view thereof; and,

FIG. 7 illustrates bottom view thereof.

The broken lines showing portions of the pickleball paddle that form no part of the claimed design.

1 Claim, 5 Drawing Sheets
